WHEEL

William J. Kreizel, Hewlett, N.Y., assignor to Chain Bike Corporation, Rockaway, N.Y., a corporation of New York

Filed Jan. 7, 1970, Ser. No. 20,798

Term of patent 14 years

Int. Cl. D12—14

U.S. Cl. D14—30

FIG. 1

FIG. 2

FIG. 4

FIG. 3

FIG. 1 is a front elevational view of the wheel, showing my new design;

FIG. 2 is a sectional view taken along the lines 2—2 of FIG. 1;

FIG. 3 is a sectional view taken along the lines 3—3 of FIG. 1; and

FIG. 4 is another sectional view along the lines 4—4 of FIG. 1.

I claim:

The ornamental design for a wheel, substantially as shown.
